Patented July 20, 1920.

UNITED STATES PATENT OFFICE.

PETER VAN VALKENBURG, OF OTTERVILLE, ONTARIO, CANADA.

MUSIC-LEAF CLIP.

1,347,135.

Specification of Letters Patent. Patented July 20, 1920.

Application filed April 1, 1919. Serial No. 286,810.

To all whom it may concern:

Be it known that I, PETER VAN VALKENBURG, citizen of the Dominion of Canada, residing at Otterville, in the Province of Ontario and Dominion of Canada, have invented certain new and useful Improvements in Music-Leaf Clips, of which the following is a specification.

This invention has as its primary object 10 to provide a novel form of clip for attachment to music leaves to serve as a convenient means whereby the leaves may be turned backwardly or forwardly.

Another object of the invention is to provide 15 a clip for the purpose stated embodying two tabs extending generally in opposite directions and at such an angle that they will assume the most convenient position for being grasped in the act of turning the leaves both backwardly and forwardly.

Another object of the invention is to so construct the clip that the same may be readily and quickly applied to and removed 20 from a music leaf and readily adjusted to any point along the margin of the leaf.

A further object of the invention is to provide 25 a clip so constructed that its attachment to and detachment from a music leaf will not in any way mutilate the leaf.

The invention has as a further object to so construct the clip that the same will be light in weight and will, therefore, not cause the leaf to which it is attached to sag.

In the accompanying drawings:

Figure 1 is a perspective view illustrating the application of the invention.

Fig. 2 is a top plan view of one form of the clip applied to a music leaf.

Fig. 3 is a side elevation of the clip shown 40 in Fig. 2.

Fig. 4 is a view similar to Fig. 2, illustrating a modified form of clip.

Fig. 5 is a view similar to Fig. 2, illustrating a further modified form of the invention.

Fig. 6 is a perspective view of one of the jaws of the clip shown in Fig. 5.

Fig. 7 is a view similar to Fig. 5 illustrating another form of the invention.

In that form of the invention shown in Figs. 2 and 3 of the drawings, the clip comprises two counterpart jaw portions indi-

cated in general by the numeral 1 and each including a shank 2 and a body 3 having a transverse flattened lip portion 4. A spring 55 5 in the form of a longitudinally split cylinder is provided with openings 6 receiving the shank portions 2 of the clip jaws 1, the edges of the cylinder at its open side bearing against the outer sides of the lip portions 4 of the said jaws whereby to yieldably hold these portions in mutual contact, it being understood that the spring serves not only to hold the jaws closed but also to hold the jaws in assembled relation and 65 that the jaws may be opened by pressing together the ends of their shank portions 2. As in the respects mentioned this clip is of a well known type, the manner of applying it to a leaf will be readily understood.

In carrying out the present invention the shank portion 2 of each clip jaw is formed with longitudinal slits or incisions 7 resulting in a finger 8 which extends generally 75 longitudinally of the respective shank 2 but is sprung outwardly from the shank as shown in Fig. 2 of the drawings. The numeral 9 indicates two finger tabs, one for each of the clip jaws, and these tabs may be 80 formed from paper, light sheet metal, cloth, or any other material or combination of materials found suitable for the purpose, although preferably flexible to a greater or less degree. Each finger tab 9 is formed 85 with an opening 10, and a shank portion 11 of each finger tab is fitted frictionally between the outer face of the respective shank portion 2 and the finger 8, as clearly shown in Fig. 2 of the drawings, the end of the finger extending through the opening 10 and being bent slightly outwardly as at 12 so as to prevent disengagement of the finger tab from the said finger.

In that form of the invention shown in 95 Fig. 4 of the drawings, the construction is practically identical with the construction just described and shown in Figs. 2 and 3 with the exception that in this modified form the lip portions 4 of the jaws are each formed with a series of teeth 13 adapting the jaws to more securely engage the music leaf to which the clip is applied.

In that form of the invention shown in

Figs. 5 and 6 of the drawings, the shank 2 of each jaw is bent laterally outwardly to form a finger piece 14 which constitutes an integral part of the jaw and takes the place 5 of the finger tab 9 heretofore described.

From the foregoing description of the invention it will be seen that the device when applied to a music leaf, constitutes a very convenient means whereby the leaf may be 10 turned either backwardly or forwardly. Inasmuch as the finger tabs 9 may be made of paper or other light material, the device as a whole may be manufactured light in weight so that its presence upon a music 15 leaf will not in any way tend to sag the leaf. Also, it will be observed, and particularly in the forms of the invention shown in Figs. 2 and 4 of the drawings, that the finger tabs 9 extend in diverging planes or, 20 in other words, at an angle less than a right angle to the planes of the respective jaws, so that when the clip is applied to a music leaf, the finger tabs will assume the most convenient position for being grasped for 25 the purpose of turning the leaf in either direction.

In that form of the invention shown in Fig. 7 of the drawing, the members of the clips adjacent their finger ends are folded 30 upon themselves as indicated by the nu-

meral 5' to provide portions corresponding to the portions 9 heretofore referred to.

Having thus described the invention, what is claimed as new is:

1. A music leaf turner including a pair of spring pressed jaws adapted for engaging a sheet of music, the rear end portions of said jaws being provided with tabs extended outwardly at acute angles to provide manipulating portions, said manipulating portions 40 being extended over the edges of the adjacent sheets of music whereby the same may be readily engaged by the fingers.

2. A music leaf turner including a pair of spring pressed jaws provided with shanks 45 at their rear end portions, said shanks being provided with spaced parallel incisions thereby forming a longitudinally extending elongated finger on each shank, and a pair of tabs having their forward portions 50 confined between said fingers and the adjacent portions of said shanks, said tabs being provided with openings receiving said fingers, the rear end portions of said fingers being engaged with said tabs and extended outwardly for disposing each tab at an acute angle to the adjacent jaw.

In testimony whereof I affix my signature.

PETER VAN VALKENBURG. [L.S.]
